CORN HUSKING MACHINE

Walter W. P. Stelter, Echo, Minn.

Application December 18, 1936, Serial No. 116,593

10 Claims. (Cl. 130—5)

This invention relates to corn husking and shredding machines.

It is one of the objects of the invention to provide novel and improved feeding means for such machines.

A further object is to provide novel and improved husking means for such machines.

It is more specifically an object of the invention to provide improvements on my previous inventions disclosed in my U. S. Patent No. 2,016,910 issued October 8, 1935, entitled "Feeder for corn shredders and the like" and in my U. S. patent entitled "Feeders for corn shredders and the like" No. 2,085,174 issued June 29, 1937.

The objects and advantages of the invention will more fully appear from the following description made in connection with the accompanying drawings, wherein like reference characters refer to the same or similar parts throughout the various views, and in which,

Fig. 1 is a view in side elevation illustrating the major portions of a corn husker and shredder embodying the invention;

Fig. 2 is a longitudinal section taken through the machine shown in Fig. 1 on approximately the line 2—2 of Fig. 3, as indicated by the arrows;

Fig. 3 is a section taken on the line 3—3 of Fig. 2, as indicated by the arrows;

Fig. 4 is a plan view looking down on portions of the husking rollers of the machine;

Fig. 5 is a view in enlarged scale of one of the band snappers of the machine.

Fig. 6 is a vertical section on an enlarged scale illustrating the snapping rollers and one of the bridging bars carried by one of the decks of the machine, and

Fig. 7 is a section taken on the line 7—7 of Fig. 6, as indicated by the arrows.

Referring to the drawings, the major parts of a combination corn husking and shredding machine are illustrated. The front end of this machine is considered to be the left end of the machine, as viewed in Fig. 1 of the drawings. Inasmuch as the present invention has to do with the mechanism for feeding the material into the snapping rollers of such a machine as is illustrated and it also has to do with the husking mechanism, it will merely be necessary to identify by number a few of the more or less standardized parts of the general machine.

The left side of the machine appearing at the left side of Fig. 3 of the drawings is designated by the numeral 6, while the right side of the machine is designated by the numeral 7. Attached to these sides are upwardly projecting side ex-

tensions or wings 8 and 9 respectively, which are not found in the usual machine, and these wings project forwardly from the rear end of the machine and they are cross connected at their forward portions by a curved plate 10 which overlies and closes off the space above the snapping rollers 11, the cutter bar 12 and the cutter head 13 which carries the cutters 14. The upper snapping roller 11 is spring pressed towards the lower snapping roller in the usual manner and the snapping rollers 11 and the cutter 13 extend between and are journaled in the forward portions of the extensions 8 and 9 in the usual relation. Of course the cutter bar 12 also extends between the extensions 8 and 9. Slightly rearwardly from the curved plate 10 the extensions 8 and 9 are additionally cross connected by a curved plate 15 of arcuate shape in cross section and having a forwardly projecting extension at its lower edge. A deck 16 inclines downwardly and rearwardly from adjacent the rear side of the lower snapping roller 11 to deliver the ears of corn snapped off the stalks by the snapping rollers 11 to the receiving ends of a plurality of husking rollers 17. These husking rollers 17 are located considerably below the level of the snapping rollers 11 and are journaled in bearings 18 carried by a pair of cross bars 19 of angular shape, which extend across between the two sides 6 and 7 of the machine. All the rollers 17 are located at the same level in parallel relation and they slant downwardly and rearwardly at rather a gradual inclination from their receiving ends toward their discharge ends. The husked corn is discharged from the husking rollers 17 into a chute 20 which feeds to an elevator 21 for delivery of the corn as into a wagon or the like.

Of course, the husking rollers 17 extend generally longitudinally of the machine and they are arranged in cooperating pairs in the usual manner, the two rollers of each pair rotating in opposite directions to form a bight for the husks therebetween. In the illustrated embodiment, the upper portions of the husking rollers 17 are provided with snapping recesses to secure a secondary snapping action to release any ears that may be carried down with stalks from the snapping rollers 11. A cross shaft 22 extends between and is journaled in the sides 6 and 7 of the machine to extend adjacent the forward ends of the various husking rollers 17 and this shaft carries beveled pinions 23 meshing with beveled gears 24 connected to the forward ends of one of each pair of husking rollers 17. The roller of a pair carrying a gear 24 also carries at its

rear end a pinion 25 in mesh with a gear 26 attached to the rear end of the cooperating husking roller 17 of the pair and it will thus be seen that all the rollers 17 are properly driven, as the shaft 22 is rotated.

In accordance with the present invention, a plurality of feed decks 27 are disposed above the husking rollers 17 between the sides 6 and 7 of the machine and to form in reality the bottom of 10 a trough, the sides of which are composed largely of the side extensions 8 and 9. These decks are of channel-shape in transverse cross section with the sides of the decks projecting upwardly and the upper edges of the sides of the decks having 15 forwardly and upwardly projecting teeth 27a formed therein. Attached by angular brackets 28 to the under side of each deck 27 are a pair of longitudinally spaced cap bearings 29. The forward bearings 29 receive within them the 20 crank portions of a forward crank shaft 30 which extends beneath and is journaled in the side walls 6 and 7 of the machine, while similarly the rear bearings 29 receive within them the crank portions of a rear crank shaft 31 which also extends between and is journaled in the sides 6 and 7. The crank portions of the two crank shafts 30 and 31 are similarly formed and set and in the illustrated embodiment each crank shaft has four crank portions for cooperation with the 25 bearings 29 for four decks 27 and the various crank portions of each crank shaft are angularly displaced from adjacent crank portions by 90°. This permits of gyration of each deck 27 as a unit as the forward crank shaft 30 is rotated and 30 it also permits differently timed gyratory motion to be imparted to the several decks.

Extending transversely between the sides of the various decks at longitudinally spaced points are cleats 27b which have upwardly and forwardly projecting teeth extending above the bottoms of the decks. The forward ends of at 40 least certain of the decks 27 are equipped with bridging bars 32 which project to points contiguous to the snapping rollers 11 and as these 45 bridging bars are originally secured to the bottoms of the decks 27, a gyratory movement will be imparted to these bridging bars as the decks are actuated. These bridging bars curve upwardly somewhat from the forward ends of the 50 decks 27 so that when the bridging bars are in their forwardmost position, the forward ends of the bridging bars will extend well into the bight between the two snapping rollers 11, as best shown in Fig. 6. These bridging bars have teeth 55 32a formed as side flanges thereon and these teeth incline upwardly and forwardly. As shown in dotted lines, Fig. 6, the forward ends of the bridging bars gyrate through the circular path and in the direction indicated. The inner sides 60 of the two outer decks 27 and both sides of the inner decks 27 have attached thereto upwardly projecting cord snapping plates 33. These plates project well above the upper edges of the sides of the decks proper and they have forwardly and 65 upwardly projecting teeth 33a formed at their upper edges. Between adjacent teeth 33a hook-shaped notches 33b are formed, as best shown in Fig. 5 of the drawings. The cord snapping plates 33 extend from adjacent the rear ends of 70 the decks 27 to points spaced slightly rearwardly from the forward ends of the decks, and the upper corners of these plates are preferably rounded as shown in Fig. 2, so as not to interfere with the travel of the material toward the 75 snapping rollers 11. The teeth 33a have hook-

shaped notches 33b extending to the forward ends of the corn snapping plates 33.

The various rollers 17 rotate in the directions indicated by the arrows in Fig. 3 and located above the rollers, extending longitudinally of the rollers, and bridging the space between adjacent pairs of rollers as well as the space immediately above the upwardly rotating portions of the two adjacent rollers of adjacent pairs, are guard bars 34 of inverted V-shape in vertical transverse cross section. These guard bars 34 have downwardly and outwardly projecting tabs at their respective ends attached to the bearings 18 for the husking rollers. Other guards 35 are attached to the sides 6 and 7 respectively of the machine to extend longitudinally above the upwardly rotating portions of the outer rollers of the two outermost pairs of rollers 17. Vertical divider plates 36 of right triangular-shape are attached to the guard bars 34 and these divider plates project upwardly from the peaks of the guard bars with the hypotenuses of the triangles slanting diagonally upwardly from points spaced rearwardly from the forward ends of the rollers a distance slightly less than half the length of 25 the rollers. Side wings 37 and 38 respectively have attaching flanges secured to the divider plates 36 and these side wings are of greater width near their lower ends than at their upper ends, they incline upwardly and rearwardly from 30 their lower ends toward their upper ends and they slant out from the divider plates 36, so that their outer edges are more rearwardly disposed than are the edges attached to the divider plates, all as shown in Figs. 2, 3 and 4.

Secured to angular-shaped brackets 27c attached to the under sides of the various decks 27 are a number of jostlers 39 and 40. These jostlers are formed of sheet material having some flexibility, such as leather or rubberized belting material, and when the machine is at rest the jostlers lie in substantially vertical planes extending longitudinally of the machine immediately above the bights between cooperating husking rollers 17. In the illustrated embodiment, each deck 27 carries two of the jostlers 39 and one jostler 40, the jostler 40 being attached to the forward portion of a deck and the two jostlers 39 being spaced rearwardly from the jostler 40 and also being spaced from each other. The jostlers 39 have a series of teeth cut in their lower edges and these teeth are capped by metal caps 41 of U-shape in horizontal cross section, the caps being secured in place by rivets or the like. The jostlers 40 have only one tooth 55 at their lower ends, this tooth being capped by a metal cap 42 similarly secured. When the decks 27 are in motion, the jostlers 39 and 40 have a gyratory motion in a vertical plane upwardly, forwardly, downwardly and rearwardly relative to the husking rollers 17 and they also, due to vibratory action, have a swinging movement transversely of the rollers 17, as indicated in dotted lines Fig. 3.

Journalized in the side extensions 8 and 9 above the forward portions of the decks 27 is a cross shaft 43. A sleeve 44 is journaled in the left side extension 8 on the shaft 43 and secured to this sleeve outwardly from the side extension 8 is a sprocket 45. The sleeve projects 70 inwardly from the side extension 8 and carries near its inner end a pinion 46. Journalized on the sleeve 44 and on the shaft 43 is a retarder drum 47 of hollow cylindrical shape, which extends between the side extensions 8 and 9. This 75

retarder drum carries transverse toothed cleats 48 on its periphery. Fixed to the shaft 43 adjacent the inner end of the sleeve 44 is an arm 49 which has journaled therein at its outer end 5 a stub shaft 50 upon which is mounted a gear 51 meshing with the pinion 46. This gear 51, in turn, carries an eccentrically disposed pin 52 to which one end of a link 53 is pivotally connected. The other end of the link 53 is pivotally 10 connected to a lug 54 attached to the inner side of the retarder drum 47.

Rearwardly disposed from the retarder drum 47 and journaled at a somewhat higher level than the shaft 43 in the side extensions 8 and 15 9 is a drum shaft 55 to which a drum 56 is secured. The drum 56 extends between the side extensions 8 and 9 and this drum has a number of radial blade-like portions with concave portions joining adjacent blade-like portions.

20 The shaft 22, although it may be driven from any moving part of the machine, is illustrated in the drawings as carrying at its right end a pulley 57 which may be driven as by a belt, not illustrated, from an engine such as that found 25 on the ordinary farm tractor. The shaft 22 may be driven in a counterclockwise direction, as viewed in Fig. 2. The crank shaft 30 carries adjacent its left end a sprocket 58 over which is trained a sprocket chain 59 and this sprocket 30 chain 59 also works over a sprocket 60 carried at the left end of shaft 22. Accordingly, the crank shaft 30 will be rotated also in a counterclockwise direction, as viewed in Fig. 2. The rotation of the shaft 30 will impart gyratory 35 movement to the various decks 27, first upwardly then forwardly then downwardly and then rearwardly successively relative to the snapping rollers 11. As bridging bars 32 are rigidly attached to the decks, these bridging bars will have 40 similar movement. Also as the jostlers 39 and 40 are attached to the decks, they will similarly gyrate. Of course the toothed sides of the decks will move with the decks as will the cord snapping decks 33.

45 The sleeve 44 for the retarder is driven from the crank shaft 30 through the medium of a sprocket 61 attached to the crank shaft, a sprocket chain 62 and a sprocket 63 attached to the left end of the sleeve 44. Accordingly, the 50 sleeve 44 is driven in a counterclockwise direction, as viewed in Fig. 1.

To drive the drum shaft 55 a stub shaft 64 is mounted in the left side extension 8 and this 55 stub shaft carries a sprocket 65. A sprocket chain 66 is trained over the sprocket 65 and a sprocket 67 carried at the left end of the drum 60 shaft 55. The lower run of this sprocket chain 66 also passes over the sprocket 45 attached to sleeve 44 and motion is imparted to the sprocket chain 66 through the medium of the sprocket 45. With this arrangement, it will be seen that the drum shaft 55 will be driven in a clockwise direction, as viewed in Figs. 1 and 2, and that, accordingly, the drum 56 will be driven in a clockwise direction. To drive the retarder shaft 43, drum shaft 65 is equipped at its right end with a sprocket 68 and a sprocket chain 69 is trained over the sprocket 68 and a sprocket 70 carried at the right 70 end of the shaft 43. Accordingly, the shaft 43 is driven in a clockwise direction, as viewed in Figs. 1 and 2.

As the shaft 43 rotates in a clockwise direction, the arm 49 will be similarly rotated but as the sleeve 44 rotates in a counterclockwise direction, the pinion 46 will be rotated in a counter-

clockwise direction. The gear 51 will, of course, rotate in a clockwise direction, as viewed in Fig. 1. As the arm 49 moves a motion will be transmitted to the retarding drum 47, first through a certain arc in a clockwise direction and thence through a certain arc less than the first mentioned arc in a counterclockwise direction. In other words, the gear 51 which has a planetary movement about the shaft 43, as well as a rotational movement about the axis of the stub 10 shaft 50, will transmit through the link 53 eccentrically connected to the gear 51, first a movement to the retarder drum 47, first in one direction and then in the opposite direction, the movement in the clockwise direction as viewed in 15 Fig. 2, being greater than the movement in the counterclockwise direction.

In operating the machine bundles of corn tied by cord in the usual manner, are thrown onto the decks 27. These decks are all differently 20 timed, so that as one deck moves forwardly, another deck moves downwardly, a third deck moves rearwardly and a fourth deck moves upwardly. The teeth 33a of the cord snapping plates 33 work into the corn so as to catch the 25 cords tying the bundles of corn together in certain of the notches 33b. The differently timed gyratory movement of the decks then causes the cords to be broken after being caught in the notches 33b. The decks, due to their gyrating 30 action spread the bundles of corn longitudinally as well as laterally and advance the corn stalks toward the snapping rollers 11. This advancing action is created very largely by the cord snapping plates 33 which work on the main body of 35 the corn and it is assisted by the transverse toothed cleats 27b which advance the finer and looser material. As the material advances to a point beneath the drum 56, this drum, if the material has built up to a high enough point, 40 acts to compress the material downwardly to a certain extent, while feeding the upper run of the material towards the retarder drum 47. Also this drum 56 acts in conjunction with the forward teeth 33a of the corn snapping plates to 45 cause these teeth to catch into the corn and thereby engage occasional cords which may not have been broken by the more rearwardly disposed teeth of the cord snapping plates. The retarder drum 47 acts on the upper strata of the 50 material, moving towards the snapping rollers 11 to prevent feed of too great quantities of the material to the snapping rollers 11 at one time. The lower portion of the retarder drum 47 moves 55 first through a certain arc in a forward direction and then through a certain arc less than the first arc in a rearward direction and thus this drum tends to spread out the material lengthwise of the machine and it prevents choking of the material at the point of entry of the 60 material into the bight between the snapping rollers.

The sides of the U-shaped decks 27 as well as the cord snapping plates 33 prevents cords and material from being carried to any appreciable 65 extent between adjacent decks to interfere with the action of the decks. The bridging bars 32 carry the material into contiguity with the bight between the snapping rollers 11 and the forward 70 ends of these bars by reason of their movement, as illustrated in Fig. 6, actually act to push the material into the bight between the snapping rollers.

Of course, the ears of corn are snapped off from the stalks by the snapping rollers 11 and the 75

stalks pass on to the cutter bar 12 and the cutter 13, while the ears in unhusked condition drop down the deck 16 onto the receiving ends of the rollers 17. The guard plates 34 and 35, of course, prevent the ears from moving to points between adjacent pairs of husking rollers and the jostlers 40 and 39, which have both a gyratory movement in a vertical plane as well as a swinging action in a plane transversely of the husking rollers 17, due to the natural vibration of the machine, strike and jostle the ears so as to agitate them and tend to align them anew with the bights between the husking rollers. In other words, the jostlers 39 and 40 give the ears of corn kicks which tends to turn the ears somewhat. In conjunction with the downward movement of the ears by gravity, these kicks imparted to the ears tend to bring the ears more in parallel alignment with the husking rollers 17 and to bring different portions of each ear adjacent the bights of these rollers, so that a much more thorough husking action is secured than would otherwise be obtained without the use of these jostlers 39 and 40. The divider plates 36 separate the ears into different channels after they have had some opportunity through the rotational movement of the husking rollers 17 and the upper jostlers 39 to align with the husking rollers. The wings 37 attached to the divider plates 36 tend to retard the movement of the ears somewhat so that a more thorough husking action can be obtained. Of course, the jostlers 39 and 40, the divider plates 36 and the wings 37 all work together to secure the desired thorough husking action. While the wings 37 tend to retard the ears the jostlers 39 tend to cause the husking rollers to take different holds upon the husks of corn. Of course, the jostlers 39 also assist materially in feeding the loose husks, stalks, etc. into the bight between husking rollers. The teeth at the lower edges of the jostlers 39 and 40 are provided with caps 41 and 42 respectively, to prevent undue wear upon these teeth. The flexibility of the material forming the jostlers permits the vibration of the machine to give the jostlers the side swinging motion transversely of the rollers 17 above referred to.

It will be seen that an efficient feeding and husking action is secured in a simple manner in accordance with the present invention. While the invention is described in connection with corn husking and shredding machines, it will be understood that it is not limited to such machines alone, inasmuch as the principles of the invention may be applied to other machines.

It will, of course, be understood that various changes may be made in the form, details, arrangement and proportions of the various parts without departure from the scope of the present invention, which generally stated, consists in the matter shown and described and set forth in the appended claims.

What is claimed is:

1. In a corn husking machine, pairs of cooperating oppositely rotating husking rolls forming bights therebetween, said rolls being parallel to each other and one pair of rolls being adjacent to another pair, fixed guard plates overlying the adjacent halves of the two adjacent rolls of adjacent pairs directing the ears to the bights between cooperating rolls, vertical dividers fixed carried by said guard plates and side wings attached to said vertical dividers, said side wings acting in conjunction with the dividers to retard the ears of corn passing over the rolls and to

assist in aligning the ears with the bight between rolls.

2. In a corn husking machine, pairs of cooperating oppositely rotating husking rolls forming bights therebetween, said rolls being parallel to each other and one pair of rolls being adjacent to another, stationary guard plates overlying the adjacent halves of the two adjacent rolls of adjacent pairs, vertical dividers carried by said guard plates, side wings attached to said dividers and moving jostlers above the rolls adjacent said dividers acting in conjunction with the guard plates, dividers and side wings to assist in aligning the ears with the bights between rolls.

3. In a corn husking machine having snapping rollers, a gyratory deck for feeding material to the snapping rollers, pairs of cooperating husking rollers underlying said deck and having receiving ends receiving from said snapping rollers and discharge ends located at a somewhat lower level than the receiving ends, there being a bight between the husking rollers of a pair, vertical dividers projecting upwardly between adjacent pairs of husking rollers, side wings attached to said dividers and moving jostlers carried by said deck, projecting downwardly therefrom adjacent said dividers and movable in respect to said dividers, said jostlers acting in conjunction with said dividers and side wings to assist in aligning the ears with the bights between cooperating husking rollers.

4. In a corn husking machine having snapping rollers, gyratory decks for feeding material to the snapping rollers, cord snapping members attached to and projecting upwardly from said decks and terminating at their upper edges in a multiplicity of forwardly inclined teeth with hook-shaped notches between adjacent teeth, pairs of cooperating husking members underlying said decks and having receiving ends receiving from said snapping rollers and discharge ends located at a somewhat lower level than the receiving ends, there being bights between the husking rollers of pairs, vertical dividers projecting upwardly between adjacent pairs of husking rollers, side wings attached to said dividers and moving jostlers carried by said decks and depending downwardly to points above the bights of said husking rollers and acting in conjunction with said dividers and side wings to assist in aligning the ears with the bights between cooperating husking rollers.

5. In a corn husking machine, pairs of cooperating oppositely rotating husking rolls forming bights therebetween, said rolls being parallel to each other and one pair of rolls being adjacent to another pair, said rolls having receiving ends located at somewhat higher levels than discharge ends, guard plates overlying adjacent portions of the two adjacent rolls of adjacent pairs and vertical dividers carried by said guard plates in spaced relation from the receiving ends of said rolls and slanting upwardly from said guard plates toward the discharge ends of the rolls.

6. The structure defined in claim 5, said guard plates being of inverted V-shape in transverse cross section to form ridges and said dividers projecting upwardly from said ridges.

7. In a corn husking machine having snapping rollers, a gyrating deck mounted to move upwardly, forwardly, downwardly and rearwardly in the order named in contiguity with the snapping rollers for feeding material to said rollers, a pair of cooperating husking rollers underlying said deck and having receiving ends receiving

from said snapping rollers and discharge ends located at a somewhat lower level than their receiving ends, said husking rollers having a bight between the same, jostlers attached to said deck 5 and depending downwardly therefrom to positions adjacent said husking rollers, said jostlers having flexibility for lateral movement relative to said husking rollers and guard plates overlying the portions of the husking rollers remote from 10 said bight, and vertical dividers carried by said guard plates in spaced relation from the receiving ends of the husking rollers and slanting upwardly from said guard plates toward the discharge ends of the husking rollers.

15 8. In a corn husking machine, pairs of cooperating oppositely rotating husking rolls forming bights therebetween, said rolls being parallel to each other and one pair of rolls being adjacent to another pair, guard plates overlying the adjacent 20 halves of the two adjacent rolls of adjacent pairs, vertical dividers carried by said guard plates and side wings attached to said vertical dividers, said side wings acting in conjunction with the dividers to retard the ears of corn passing over the rolls 25 and to assist in aligning the ears with the bight between rolls, said dividers projecting upwardly from said rolls and having upper edges joining said guard plates in spaced relation from the receiving ends of the rolls, said upper edges slanting upwardly and toward the discharge ends of the rolls.

9. In a corn husking machine, pairs of cooper-

ating oppositely rotating husking rolls forming bights therebetween, said rolls being parallel to each other and one pair of rolls being adjacent to another pair, guard plates overlying the adjacent 5 halves of the two adjacent rolls of adjacent pairs, vertical dividers carried by said guard plates and side wings attached to said vertical dividers, said side wings acting in conjunction with the dividers to retard the ears of corn passing over the rolls and to assist in aligning the ears with the bight between rolls, said dividers being spaced from the receiving ends of the rolls and being of triangular shape with the hypotenuse edges of the triangle slanting upwardly and 10 toward the discharge ends of the rolls.

15 10. In a corn husking machine, pairs of cooperating oppositely rotating husking rolls forming bights therebetween, said rolls being parallel to each other and one pair of rolls being adjacent to another pair, guard plates overlying the adjacent 20 halves of the two adjacent rolls of adjacent pairs, vertical dividers carried by said guard plates and side wings attached to said vertical dividers, said side wings acting in conjunction with the dividers to retard the ears of corn passing over the rolls 25 and to assist in aligning the ears with the bight between the rolls, said wings slanting outwardly and somewhat toward the discharge ends of said rolls from said dividers and being pitched upwardly and toward the discharge ends of said 30 rolls from their lower end.

WALTER W. P. STELTER.
